LEATHER WRIST WATCH STRAP

Albert H. Sauer, Jr., Cincinnati, Ohio

Application February 25, 1936, Serial No. 65,684

7 Claims. (Cl. 224—4)

This invention relates to improvements in wrist watch straps, and particularly to improvements in leather wrist watch straps.

One of the principal objects of the present invention is to provide a leather wrist watch strap in which the forces and strains are counteracted to provide a strap having greater strength and durability.

Another object of this invention is the provision of a leather wrist watch strap composed of the usual separable sections, and each section in turn being formed from a plurality of pieces or parts whereby an infinite number of designs may result while utilizing the general make-up or structure of the strap.

A further object of the invention is to provide an improved strap capable of modification upon the structure as disclosed in the United States Patent No. 2,035,671, issued to Albert H. Sauer, Jr., on March 31, 1936.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Fig. 1 is a plan view of the improved wrist watch strap of this invention as attached to an ordinary wrist watch;

Fig. 2 is a longitudinal sectional view of the strap as seen from line 2—2 on Fig. 1;

Fig. 3 is a perspective view of the several parts entering into the manufacture of one section of the strap as illustrated in Figs. 1 and 2;

Fig. 4 is a perspective view of the individual parts utilized in the manufacture of the second section of the strap of Figs. 1 and 2;

Fig. 5 is a plan view similar to Fig. 1 but showing a modification of the invention;

Fig. 6 is a sectional view of the modified strap as shown in Fig. 5 and as seen from line 6—6 on said Fig. 5;

Fig. 7 is a perspective view of the parts, and as utilized in the manufacture of one section of the strap of Fig. 6;

Fig. 8 is a perspective view of the parts of the second section of the strap of Fig. 6;

Fig. 9 is a plan view similar to Figs. 1 and 5 and illustrating a further modification of the invention;

Fig. 10 is a sectional view of the strap of Fig. 9 as seen from line 10—10 on said Fig. 9; and

Figs. 11 and 12 are respectively perspective views of the additional or different piece which is utilized in conjunction with other pieces of the straps of Figs. 1 and 5 to make or complete the sections of the strap of Figs. 9 and 10.

Throughout the several views of the drawings similar reference characters are employed to denote the same or similar parts.

As was noted above, this invention pertains to improvements in the construction of a leather wrist watch strap in which the strains and forces on said strap are better compensated for, and to provide an improved construction whereby a greater number of designs in wrist watch straps may be made while utilizing the principles of construction as set forth hereinafter. At the same time this invention discloses improved constructional features and details over the United States Patent No. 2,035,671 of Albert H. Sauer, Jr., which issued March 31, 1936.

Specifically referring to the drawings, each of the modified straps there illustrated comprises a tongue section indicated in general by the reference numeral 15 and a buckle section indicated in general by the reference numeral 16. The said sections each have their inner ends connected to a wrist watch 17. The tongue section as seen in Figs. 1 to 4 inclusive comprises an inner part 18, a center or ornamental part 19, and the tongue part 20.

As seen in Fig. 3, the inner part 18 comprises a piece of leather folded on itself to provide at the ends thereof loops or openings 21 and 22, the folds being secured to one another by means of a line of stitches 23. The loop or opening 21 is adapted to receive the wrist watch attaching pin 24, while the other loop 22 is utilized for attaching the center ornamental part to the end part. This central ornamental part 19 may be made up of one or more pieces, which as shown in Fig. 1 comprises three separate pieces. These pieces as shown in Fig. 3 are a ring 25 formed of a leather thong such as more fully illustrated and described in the co-pending application of Albert Herman Sauer, Jr., Serial No. 759,539, now Patent No. 2,035,672, issued March 31, 1936, for "Article of manufacture and the method of making same" which was filed December 28, 1934. This leather thong has its ends abutting one another and secured in this position by means of a metal clip or tie 26. This ring 25 has a portion thereof disposed in the opening or loop 22 of the watch attaching part 18. The ring 25 has an

additional portion thereof, and preferably including the metal fastening clip 26, disposed in an opening or loop 27 of the connector 28 of the central ornamental section 19. The connector 28, similar to the watch attaching part 18, is formed of a single piece of leather folded on itself to provide the aforementioned loop or opening 27 and a second loop or opening 29, the folds of the connecting section 28 being secured in position by a line of stitching 30. Received in the loop or opening 29 is a portion of a second ring 31 which is similar in all respects to the ring 25 and above described. A second portion of the ring 31 is received in a loop or opening 32 formed at the inner end of the tongue part 20. This tongue 20 is formed of a single piece of material folded on itself with the ends thereof overlapping one another and secured by a line of stitching 33. It will be noted from the drawings that the overlapping of the ends of the strip which forms the tongue is adjacent to the loop or opening 32, wherefore the major portion of the tongue part is of uniform thickness and devoid of folds or bumps. The major portion of the tongue folds 25 are cemented to one another so as to maintain same in a fixed desired position, and this tongue portion is provided with a series of apertures or holes 34 to receive the catch of the buckle.

The second section 16 of the strap has its parts illustrated in perspective in Fig. 4. As there shown, these parts consist of an inner watch attaching part 35 which is similar in all respects to the watch attaching part 18. This watch attaching part 35 is connected with the watch 17 in the same manner that the watch attaching part 23 is connected therewith, and is connected with a central ornamental part composed of rings 36 and 37, connected to one another by the connecting member 38, which are similar in construction to the rings 25 and 31 and their connecting member 28. The ring 37 is adapted to have a portion thereof received in a loop or opening 39 formed at one end of the buckle supporting part 40. This buckle supporting part 40, similar to the tongue part 20, is formed of a single strip of leather folded on itself to provide the loop 39 at one end thereof, and a second loop 41 at its other end. It will be noted that the ends of the strip overlap one another adjacent to the loop 40 and are secured by means of stitching 42. The loop 39 at the other end is likewise permanently formed by means of a line of stitching 43. One end of the leather strip forming the buckle part 40 adjacent to the line of stitching 42 is utilized to form an elongated loop 44, see Fig. 2, receiving the lower surface of the tongue retaining loop 45, the loop 44 being permanently formed by means of a line of stitching 46. It should be noted at this time that the body portion of the leather between the lines of stitching 43 and 42 are cemented to one another to retain same in position.

Received in the outermost loop 41 of the buckle part 40 is the pin 46 for the buckle frame 47 and the buckle clasp 48. The inner end of the buckle clasp 48 is disposed in a cut-away or recessed portion 49 formed in the buckle part 40.

From the foregoing it will be seen that each of the several parts of each section of the watch strap is substantially independently formed and simply hooked or threaded through each other to effect a complete connection one with the other, instead of connecting these parts directly by means of stitches or the like. Due to this particular arrangement the strains and stresses are taken primarily by the fibers of the leather

of the strap instead of by stitches which connect the several parts to one another.

In the modified strap illustrated in Figs. 5 to 8 inclusive, the tongue part 50 and buckle part 51 are respectively sewed or stitched to the ornamental center sections instead of looped therewith. This construction is clearly illustrated in Fig. 7.

As seen in Fig. 7, use is made of a watch attaching part 52 which is similar in all respects to the watch-attaching parts 18 and 35. Instead of the watch attaching part 52 receiving therein a portion of an ornamental ring, it instead receives therein the body portion of a loop 53 which has its ends 54 and 55 projecting free therefrom, the free ends 54 and 55 being spaced by an ornamental metallic member 56 located immediately at the base of the loop 53. The free ends 54 and 55 are disposed between the free gaping ends 57 and 58 of the tongue section 50. This tongue section 50 is similar to the one illustrated in the above-noted co-pending application Serial No. 752,494. This tongue part 50, similar to the tongue part 20, is formed of a single piece of leather with the body portion overlapped and secured to one another, and with the ends free and gaping as illustrated at 57 and 58. After the ends 54 and 55 of the connecting thongs are placed between the gaping ends 57 and 58, the parts are placed on top of one another and secured in position by means of stitching 59, see Fig. 5.

The buckle section of the strap of Figs. 5 and 6 is similar in construction to the tongue section just described and comprises a watch attaching part 60 and a central ornamental connecting part 61 which are respectively similar to the parts of the tongue section just described. The free ends of the connecting part 61 are disposed between the free and gaping ends 62 and 63 of the buckle part 64 which is formed of a single piece of material folded on itself to provide a loop or opening 65 at one end thereof, the parts being secured in position by a line of stitching 66. Immediately behind the stitching 66 the folds of the buckle part 51 are separated to provide an opening for one side of the tongue loop 67, this tongue loop opening being permanently provided by means of a line of stitching 68. The free and gaping ends 62 and 63 of the buckle part 51 are secured to the free ends of the connecting section 61 by means of stitches 69.

From the foregoing it will be noted that the strap of Figs. 5 to 8 inclusive is composed of certain parts of the strap illustrated in Figs. 3 and 4, and of certain parts illustrated in the above-mentioned co-pending application. With this construction additional designs may be provided over and above the designs as may be effected by either the construction in Figs. 1 to 4 inclusive or the construction of the co-pending application. In Figs. 9 to 12 inclusive there is illustrated a further modification in the construction details of a wrist watch strap which strap again combines parts or constructional features of the strap illustrated in Figs. 1 to 8 inclusive, and in the above referred to co-pending application. As will be noted from Figs. 9 and 10 the buckle part 70 and the tongue part 71 are identical with the buckle part 40 and tongue part 20 of Figs. 1 and 2, while the connecting ornamental sections 72 and 73 are substantially identical with the connecting sections illustrated in Figs. 5 and 6. The inner watch attaching parts 74 and 75, however, are different from the other

watch attaching parts illustrated in the drawings but are substantially identical with that illustrated in the co-pending application Serial No. 752,494. As shown in Figs. 11 and 12, each of these watch attaching parts is formed of a single piece of leather folded on itself to provide the watch pin bar loops 76 and 77 with the ends free and gaping as shown at 78 and 79. The free and gaping ends 78 and 79 receive between them the free projecting ends of the ornamental connecting sections 72 and 73, and these parts are secured to one another by the stitching 80.

By comparison of Figs. 5 and 9 it will be noted that the strap designs there illustrated are substantially the reverse of one another, having the loops 53 in one instance adjacent the tongue and buckle sections, and in the other instance adjacent the wrist watch.

From the foregoing it will now be noted that there has been provided by this invention a technique of wrist watch manufacture which meets all of the requirements for a comfortable wrist watch strap such as provided by leather or other flexible material, while, at the same time, providing a structure which will produce an infinite variety of strap designs.

What is claimed is:

1. A leather wrist watch strap of the class described having in combination a pair of strap sections, each section comprising an inner watch attaching part, an outer part forming in one section the buckle support and in the other section the tongue, a center connecting decorative part having its one end connected with the watch attaching part and its other end connected with the outer part, and either said watch attaching part or outer part having a loop at its end adjacent the center connecting ornamental part through which said center ornamental part passes to effect the connection, and the remaining watch attaching or outer parts having their adjacent ends free and gaping to receive the adjacent ends of the center connecting decorative parts and said ends being stitched to one another to effect the connection.

2. In a wrist watch strap of the class described the combination with a wrist watch having pin bars at the ends thereof, of a pair of strap sections each having an inner watch attaching part formed of a single piece of material folded on itself to provide a pin bar loop and with the ends thereof free and gaping, a center connecting ornamental part having its ends disposed between the free and gaping ends of the watch attaching parts, and a tongue part at the free end of one of the connecting sections and a buckle carrying part at the free end of the other connecting section and said tongue and buckle parts having loops formed at the ends thereof adjacent the connecting part through which said connecting part passes.

3. In a leather wrist watch strap of the class described the combination of a watch attaching part, a tongue part, a center ornamental connecting part, and means for connecting the adjacent ends of the center connecting part with the watch attaching part and tongue part com-

prising in at least one of said parts a loop through which a portion of the connecting part passes, and in the other connection having the ends free and gaping to receive the adjacent end of the center connecting part.

4. In a leather wrist watch strap of the class described the combination of an inner watch attaching part, an outer buckle carrying part, a center connecting ornamental part, and means for connecting the ends of said center connecting part to the adjacent ends of the watch attaching part and buckle part comprising in at least one of said connections a loop through which a portion of the center ornamental connecting part passes, and in the other connection having the ends free and gaping to receive the ends of the adjacent center connecting part.

5. In a wrist watch strap of the class described the combination of a pair of strap sections, each having an inner watch attaching part formed of a single piece of material folded on itself to provide a pair of transverse loops and a center ornamental connecting part having a portion thereof extending through one of the loops of the watch attaching part, a tongue at the free end of one of the center ornamental connecting parts, a buckle carrying part at the free end of the other center ornamental connecting part, and said tongue and buckle carrying part each having gaping ends to receive the adjacent end of the center connecting ornamental parts and which gaping ends and embraced center ornamental connecting part end are respectively secured to one another to effect the connection of the tongue and buckle carrying parts to their center ornamental connecting part.

6. In a leather wrist watch strap of the class described the combination of a watch attaching part, a tongue part, a center ornamental connecting part, and means for connecting the adjacent ends of the center ornamental connecting part with the watch attaching part and tongue part, comprising a transverse loop on said watch attaching part through which a portion of the center ornamental connecting part passes, and the tongue part having, adjacent the center ornamental connecting part, gaping ends to receive the center ornamental connecting part and which gaping ends and embraced center ornamental connecting part end are secured to one another.

7. In a leather wrist watch strap of the class described the combination of a watch attaching part, an outer buckle carrying part, a center ornamental connecting part, and means for connecting the adjacent ends of the center ornamental connecting part to the watch attaching part and buckle carrying part, comprising a transverse loop on said watch attaching part through which the portion of the center ornamental connection part passes, and the buckle carrying part having, adjacent the center ornamental connecting part, ends gaping to receive the center ornamental connecting part and which gaping ends and embraced center ornamental connecting part are secured to one another.
